UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,036,756.

Specification of Letters Patent. Patented Aug. 27, 1912.

Application filed June 16, 1911. Serial No. 633,624.

To all whom it may concern:

Be it known that I, SIDNEY D. WALDON, a citizen of the United States, and resident of Detroit, Wayne county, State of Michigan, 5 have invented certain new and useful Improvements in Hydrocarbon-Motors, of which the following is a specification.

This invention relates to hydrocarbon motors and particularly to the mechanism 10 for oiling the crank shaft and other bearings and the cylinder walls of such motors.

The invention is illustrated as applied to a multi-cylinder motor and the drawings may be described as follows:

15 Figure 1 is a vertical transverse section through a motor of the above type; Fig. 2 is a plan view of the motor with the cylinders in horizontal section; Fig. 3 is a modified detail; Fig. 4 is a sectional view 20 of the oil strainer and relief valve; and Fig. 5 is a sectional view of the three-way valve.

In this invention the main bearings of the motor crank shaft are lubricated by a 25 constant supply of oil under pressure, fed directly to them by a pump geared to an operating part of the motor, preferably the cam shaft, the speed of the pump therefore being in direct proportion to the speed of 30 the motor. The pump draws the oil from the bottom of the crank case or sump where it has drained and forces it through suitable piping and screens to the crank shaft bearings. In the piping from the pump to the 35 bearings there is arranged a relief valve set to operate at a predetermined pressure so that after the motor has reached a certain speed and the pressure in the pipe line has consequently reached a certain degree, this 40 relief valve will be operated and the oil passing through the valve will be conveyed to another part of the motor. In one of the embodiments of the invention this excess supply of oil is conveyed directly to 45 the crank case where it is taken up by the pump and worked into the system again.

In another embodiment of the invention there is a forked outlet from the upper side of the relief valve and one of the branches 50 of this outlet runs directly to the crank case and the other branch runs to the walls of the various cylinders, preferably on that side of the cylinder which receives the thrust of the piston on its working stroke. 55 This forked outlet is shown as controlled

by a 3-way valve which is operated by the motor throttle connection so that the 3-way valve connects the relief valve directly with the crank case when the throttle is in nearly closed position and with the cylinder walls 60 when the throttle is wide open or nearly so.

By the above arrangement it will be seen that, as long as there is sufficient oil in the system, oil will always be passing through the relief valve when the motor is running 65 at comparatively high speed and regardless of the power being generated, but the destination of this excess is determined by the position of the 3-way valve above referred to, and when the motor is operating under 70 a light load, though the speed be high, the said 3-way valve will be in position to direct the excess flow into the crank case, whereas when the motor is operating under full load, as with the throttle wide open, 75 the excess oil will be delivered to the cylinder walls on that side thereof upon which there is the greatest side thrust, thus supplying an extra amount of lubrication 80 thereto.

The above arrangement is particularly advantageous since it is undesirable to supply oil to the cylinder walls except when the throttle is comparatively well open for the reason that at all other times only a 85 partial charge is taken into the cylinders thereby creating a partial vacuum therein, and if oil is fed directly to the cylinder walls at such times some of it will be drawn into the combustion space by reason of the 90 partial vacuum therein and it will be mixed with the charge and burned therein, creating an undesirably smoky exhaust. This statement is qualified somewhat by the fact that the oil supply to the cylinders is not 95 so objectionable at high speed even though the throttle is only partially open for the reason that at such times the cylinders are not very thoroughly cleaned out on the exhaust stroke and the partial vacuum is 100 not so noticeable even though the throttle may be only partly open. On motors with very large and free valves, however, the position of the throttle valve should in some way control the amount of oil fed to 105 the cylinder walls.

Referring to the drawings, 10 represents the crank case of a hydrocarbon motor upon which the cylinders 11 are mounted. The 110 crank shaft 12 is supported in the crank case

in bearings 13 as by blocks 14. The lower half of the crank case is in the form of a removable cover 15 which forms a sump 16 for the oil thrown from the crank shaft and other bearings within the crank case. Also mounted in the crank case are cam shafts 17 and 18 driven from the crank shaft in any well known way. The pistons 19 and connecting rods 20 are shown in Fig. 1.

It will be understood that the crank shaft 12 turns clockwise or in the direction of the arrow shown in Fig. 1 thereby causing a greater side thrust of the piston 19 on the left side of the cylinder wall when the piston is on its firing stroke, as shown in Fig. 1.

The main oil circulation system includes the pump 21, preferably a gear pump driven through shaft 22 and spiral gears 23 from the cam shaft 17, piping 24 leading to a screen or filter 25, manifold 26, branch pipes 27, and conduits 28, which lead directly to the crank shaft bearings 13 and to the interior of the bored out crank shaft 12. The oil may be conveyed to the connecting rod bearings through suitable leads from the opening 29 through the center of the crank shaft.

The above circulation system gives a constant supply of oil under pressure to all of the crank shaft bearings and from these bearings the oil is thrown by the crank shaft to all parts of the crank case for the purpose of lubricating the cam shaft and other bearings therein.

Suitably connected with the manifold 26 or some other part of the main oil circulation system, is a relief valve 30. In Fig. 4 this relief valve is shown as formed integral with the filter 25. The screen 31 of the filter is held in place by a spring 32 and is adapted to be removed through an opening above the screen upon removal of the cap 33. The relief valve consists of a disk 34 properly seated by a spring 35 adjusted by the screw cap 36. The disk and spring may be removed for cleaning by unscrewing the detachable part 37 of the valve casing. There is an outlet 38 in the relief valve casing 50 above the disk 34 through which the excess oil passes when the valve is operated from pressure within the oil circulation system.

The outlet 38 is controlled by a 3-way valve 39, shown in section in Fig. 5, which 55 3-way valve determines the direction taken by the excess oil after it leaves the relief valve. The branch pipe 40 leading from the 3-way valve 39 conveys the excess oil directly into the crank case 10, thereby merely forming an overflow for the excess. The branch pipe 41 leading from the 3-way valve 39 conveys the excess oil to a manifold 42 and thence through branch pipes 43 to the walls of the cylinders 11, preferably on that 65 side of the cylinder where there is the greatest

amount of side thrust, which is the left side of the cylinder as illustrated in Fig. 1 as heretofore explained. The 3-way valve 39 is connected with an arm 44 which is controlled by a rod 45 mounted to slide in a bracket 46 suitably supported on the crank case. In the position of the parts shown in the drawings the valve 39 permits the excess oil from the relief valve 30 to flow directly into the crank case 10 through the pipe 40. By giving the valve 39 a quarter turn this excess oil passes straight through the valve 39 and into the pipe 41 and from thence to the cylinder walls for lubricating the latter.

In Fig. 2 the motor intake pipe is shown at 47 in which is the main throttle valve 48 operated by arm 49. This arm is controlled by a rod 50 suitably connected with the accelerator pedal or other manual control levers, not shown. The rod 50 slides in the eye of an arm 51 on the bracket 46 and moves in the direction of the arrow shown in Fig. 2 for opening the throttle 48. A pin 52 on the rod 50 slides in the slot 53 in the enlarged end of the rod 45 and it will be seen that when the rod 50 is moved to open the throttle the rod 45 is simultaneously moved to give the 3-way valve 39 a quarter turn thereby allowing the excess oil to be fed to the cylinder walls when the motor throttle is open. When the throttle is closed the pin 52 sliding in the slot 53 moves the valve 39 to the position in which it is shown in Fig. 5 thereby directing the excess oil into the crank case and shutting it off from the cylinder walls.

In Fig. 3 a slight modification of the invention is shown in which the 3-way valve 39 is omitted and all of the excess oil passing through the relief valve 30 is conveyed directly to the cylinder walls through the pipe 45. This simplifies the connections and this construction is suitable for some types of motors.

Having thus described my invention, what I claim is:

1. In a hydrocarbon motor oiling system, the combination with means for feeding oil to the motor crank case, of means controlled by the pressure within the crank case feeding means for feeding oil to the motor cylinder.

2. In a hydrocarbon motor oiling system, the combination with means for feeding oil to the motor crank case comprising a pressure system, of means controlled by the pressure within said system for feeding oil to the motor cylinder.

3. In a hydrocarbon motor oiling system, the combination with means for normally feeding oil to certain parts of the motor, of means controlled by the rise of pressure in said normal feeding means for feeding oil to other parts of the motor.

4. In a hydrocarbon motor, the combination with means operated by the motor crank shaft for feeding oil under pressure to the crank shaft bearings, of means controlled by said pressure for feeding oil to the cylinder wall. 60
5. In a hydrocarbon motor, the combination with means for feeding oil under pressure to the crank shaft bearings and including a pressure relief valve, of means for conveying the oil passing said relief valve to the motor cylinder for lubricating the piston therein. 65
6. The combination with a hydrocarbon motor, of means for supplying lubricating oil between the piston and cylinder on that side of the cylinder receiving the side thrust on the firing stroke of the piston. 70
7. The combination with a hydrocarbon motor, of means for supplying lubricating oil to the cylinder wall under pressure on that side of the cylinder receiving the side thrust on the firing stroke of the piston. 75
8. In a hydrocarbon motor, the combination with means for feeding oil under pressure to the crank shaft bearings and including a pressure relief valve, of means for conveying the oil passing said relief valve to the motor cylinder wall on that side of the cylinder receiving the side thrust on the firing stroke of the piston. 80
9. In an oiling system for a multi-cylinder hydrocarbon motor, the combination of a pump in the motor crank case operated by the motor for withdrawing oil from the crank case, main and branch leads from the pump to the motor crank shaft bearings, a relief valve in the main lead adapted to open at a predetermined pressure, and main and branch leads from the relief valve to the motor cylinder walls, whereby the cylinder walls are supplied with oil only when the pressure in the main pump lead reaches a predetermined height. 85
10. In a hydrocarbon motor oiling system, the combination with means for feeding oil to the motor crank case, of means controlled by the motor speed and throttle opening for feeding oil to the motor cylinder. 90
11. In a hydrocarbon motor oiling system, the combination with means for feeding oil to the motor crank case, of means operative only at comparatively high speed of the motor and considerable throttle opening, for feeding oil to the motor cylinder. 95
12. In a hydrocarbon motor oiling system, the combination with a pump for withdrawing oil from the motor crank case, piping from the pump to the motor crank shaft bearings, a relief valve in said piping adapted to open at a predetermined pressure, piping from said relief valve having two branches running respectively to the motor cylinders and to the crank case, a valve in said latter piping for connecting the relief valve with either of said branches, a motor throttle control device, and a connection from said device to said valve for placing said relief valve in communication with the cylinder branch pipe when the motor throttle is considerably opened and with the crank case branch pipe when the motor throttle is more nearly closed. 100
13. In a hydrocarbon motor, the combination with an oil pump and piping leading therefrom, of a casing mounted on the crank case and having a connection with said piping, an oil strainer in the casing, a relief valve in the casing, oil outlets from the casing below and above said relief valve, and piping leading from said outlets respectively to the motor crank shaft bearings and to an overflow. 105
14. In a hydrocarbon motor, the combination with an oil pump and piping leading therefrom, of a casing mounted on the crank case and having a connection with said piping, an oil strainer in the casing, a relief valve in the casing, oil outlets from the casing below and above said relief valve, and piping leading from said outlets respectively to the motor crank shaft bearings and to the motor cylinder walls. 110
15. In a hydrocarbon motor oiling system, the combination with the motor crank case, of a casing mounted thereon comprising a strainer part and a relief valve part, an inlet connection on the strainer part, an outlet connection between the strainer and the relief valve, and an overflow outlet connection beyond the relief valve. 115
16. In a hydrocarbon motor, the combination with the oil pump and piping leading therefrom, of a casing having a connection with said piping, a relief valve in the casing, oil outlets from the casing below and above said relief valve, and piping leading from said outlets respectively to the motor crank shaft bearings and to the motor cylinder walls. 120

In testimony whereof I affix my signature in the presence of two witnesses.
